Victor J. Evans

ATTORNEY.

UNITED STATES PATENT OFFICE

JOSEPH NEUMAN, OF ELIZABETH, NEW JERSEY

MATTRESS

Application filed June 28, 1929. Serial No. 374,600.

This invention relates to mattresses and to the method of making the same, an object being to provide a mattress wherein the edge rolls, which are separately formed, are secured to the opposite edges of a strip and the latter attached to the mattress springs with the rolls housed within the cover before the latter is closed, instead of forming the rolls upon the edges or corners of the mattress after the cover is closed. This reduces the time and labor required for making a mattress, and results in an improved product, and in addition provides a mattress of improved appearance.

With the above and other objects in view, the invention further includes the following novel features and details of construction, to be hereinafter more fully described, illustrated in the accompanying drawings and pointed out in the appended claim.

In the drawings:—

Figure 1 is a fragmentary plan view showing one corner of a mattress constructed in accordance with the invention.

Figure 2 is an enlarged section on the line 2—2 of Figure 1.

Figure 3 is a sectional view taken through one edge of the mattress before the upper and lower pads and mattress cover are applied.

Figure 4 is a fragmentary elevation of the subject matter of Figure 3.

Referring to the drawings in detail where in like characters of reference denote corresponding parts, the mattress as shown includes a plurality of spiral springs 10, which, as is usual in mattresses of this type are enclosed in fabric coverings 11. These springs are arranged in rows between upper and lower pads 12 and 13 respectively, while a cover 14 encloses the springs and pads and this cover may be quilted as shown at 15.

Usually, in mattresses of this character a roll is formed along the edges or corners of the mattress by stitching through adjacent portions of the top and sides of the mattress. This method of forming the roll has many disadvantages, the principal disadvantage being that the felt pads are stretched and separated along the line of stitching.

The above and other disadvantages are

overcome in the present invention by providing a fabric strip 16 which carries at its opposite edges rolls 17. These rolls are formed of fabric covered felt 18 or other suitable material which encloses a wire or other stiffening rod 19. A wire or stiffening rod 20 is enclosed by the fabric strip adjacent the rolls 17.

The springs 10 are arranged between the pads 12 and 13. The side and end strips 16 are attached to the outermost row of springs as by stitches 23 and a thin pad of felt or other material 24 is placed around the strip 16. The rolls 17 are folded inward upon the springs along the edges of the pads 12 and 13 and the top, bottom and sides of the cover are secured together and taped as shown at 25. The rolls 17 are thus enclosed within the mattress cover.

The invention is susceptible of various changes in its form, proportions and minor details of construction and the right is herein reserved to make such changes as properly fall within the scope of the appended claim.

Having described the invention what is claimed is:—

In a mattress construction, rows of coiled springs, a cellular cover for each spring, pads arranged above and below said springs, a strip of flexible material extending around the sides and ends of the mattress and secured to the covering of the springs, edge rolls secured along the opposed longitudinal edges of the strip, spaced parallel stiffening rods, one of said rods being passed centrally through each edge roll and the other of said rods being encased in said flexible strip immediately beneath the roll, an outer covering for the mattress, and said edge rolls being flexed inwardly and arranged to lie above and below the springs within the confines of the mattress.

In testimony whereof I affix my signature
JOSEPH NEUMAN
